UNITED STATES PATENT OFFICE.

FRANK J. LASKOWSKI, OF ALLENTOWN, PENNSYLVANIA, ASSIGNOR OF ONE-HALF TO
FREDERICK H. FRIED, OF ALLENTOWN, PENNSYLVANIA.

FOLDING AND RECLINING CHAIR.

1,114,153.

Specification of Letters Patent.

Patented Oct. 20, 1914.

Application filed September 22, 1913. Serial No. 791,175.

To all whom it may concern:

Be it known that I, FRANK J. LASKOWSKI, a citizen of the United States, residing at Allentown, in the county of Lehigh and State of Pennsylvania, have invented certain new and useful Improvements in Folding and Reclining Chairs, of which the following is a specification, reference being had to the accompanying drawings.

10 This invention relates to new and useful improvements in chairs, and more particularly to that class of chairs which may be readily folded into a compact form so as to take up a minimum amount of space.

15 An object of this invention is the provision of a folding chair which may be quickly and easily adjusted to any desired reclining position by the person who is occupying the chair.

20 Still another object of this invention is the provision of a chair which may be readily adjusted to a reclining position, the back of the chair and foot rest being adjusted simultaneously so that the foot rest is in position for use, regardless of the angle of inclination of the chair.

25 With these and other objects in view, which will become fully apparent as the description proceeds, my invention consists of certain novel constructions, combinations and arrangements of parts to be hereinafter more fully described, claimed, and illustrated in the accompanying drawings, in which—

Figure 1 is a perspective view of the chair 35 in set-up position. Fig. 2 is a side elevation thereof in folded position. Fig. 3 is a side elevation of a chair in a reclining position. Fig. 4 is a back elevation of the chair. Fig. 5 is a detail view of the rack. Fig. 6 is a 40 detail view of the bolt for holding the back in raised position, and Fig. 7 is a perspective view of the bar which engages with the fastening bolt for holding the chair in raised position.

45 Referring more particularly to the drawings, the numeral 1 designates a pair of supporting legs which are pivotally connected intermediate of their ends, as at 2, to the medial portions of the supporting legs 3.

50 When the chair is in set-up position, the legs are crossed, and pivotally connected to the upper ends of the legs 1, as at 3', are standards 4 which are beveled at their lower ends, as at 5, and rest on the legs 3 near the 55 lower ends thereof. Links 6 are pivotally

connected at their opposite ends to the legs 3 and the standards 4 to limit the outward movement of the standards on the legs, and thereby limit the relative spreading movement of the legs 1 and 3, as clearly disclosed 60 in Figs. 1 and 3 of the drawings. The arm rests 7 have secured to their lower face, at the outer ends thereof, rack members 8, in which are formed longitudinal slots 9, the rack members being provided with inwardly 65 extending teeth 11. Secured to the upper ends of the standards are plates 12, the plates being offset as at 13 to form a space between the plates and the standards 4, in which the rack members 8 are slidably 70 disposed. Pins 14 are arranged in aligned openings in the upper ends of the standards and the plates 12, the pins slidably engaging in the slots 9 in the members 8 and adapted to engage the teeth 11 thereof to maintain 75 the arm rests 7 in adjusted position. Uprights 15, forming the back frame of the chair, are pivotally connected intermediate of their ends to the rear ends of the arm rests 7, the uprights being connected at their 80 upper extremities by a suitable cross bar 16. Pivotally connected to the vertical members 15 near the lower ends thereof, by rods 17, are the substantially horizontal side members 18 of the chair frame, the members 18 85 being pivotally connected near their forward ends to the pivot rods 3' which connect the upper ends of the legs 1 to the standards 4. The rods 17 are formed on one end with spaced heads 19, and the heads are adapted 90 to rest on the upper face of the legs 3 and support the chair frame thereon, and also form the pivotal point of the chair when the chair is adjusted to different angles of inclination. The opposite end of the rods 17 95 extend through openings in the member 15 and the member 18, and a washer or plate 17^a is slidably disposed on each rod to bear against the inner faces of the members 18. The washers are held in position on the 100 rods by the cotter pins 17^b which are disposed through suitable openings formed in the rods.

Secured to the upper faces of the legs 3 at the upper ends thereof, are bars 20 which 105 are curved, as at 21, near their upper ends to form loops 22, the loops being adapted to engage between the spaced heads of the bolts to hold the vertical members 15 in position. It will be seen in Fig. 7, of the drawings, 110

that the loops 22 are elongated and enlarged at the throat, so that upon movement of the vertical members 15 in the proper direction, the rods 17 may be readily removed from the members to allow folding of the chair.

Pivots secured to the forward extremities of the bars 18, are supporting bars 23, which are provided near their lower ends with rearwardly extending apertured lugs 24 in which the foot rest 25 is pivotally mounted. The lower extremities of the supporting bars 23 are offset inwardly, as at 26, to provide stops to limit the movement of the foot rest 25. Link rods 27 are pivotally connected at their rear ends to the lower end of the members 15, and are also pivotally connected at the forward ends to the intermediate portions of the supporting bars 23 of the foot rest, so that upon movement 20 of the back of the chair, the foot rest will also be moved, whereby the foot rest is always maintained in a position for use.

The upholstery of the chair comprises a strip of heavy flexible cloth or other suitable material 28, which is secured at one end to the cross bar 16 which connects the upper ends of the members 15, the strip extending downwardly between the members 15 and extends horizontally of the chair below the bars 18 to form the seat of the chair. A transversely extending bracket 29, having its upper ends offset, as at 30, is secured to the bars 18 near the forward ends thereof, the upper face of the bracket being curved so as 30 to present a smooth surface to the body of the person occupying the chair. It will be seen that the bracket 29 forms the forward cross bar of the chair frame and the strip 35 28 is connected to the foot rest 25, as at 31. It will be understood that the flexible strip 28 readily conforms to the shape of the body of the person seated in the chair, and when the chair is in a reclining position, the strip 40 extends the whole length of the body.

When it is desired to adjust the angle of the inclination of the back and foot rest of the chair, the arm rests 7 are raised so as to disengage the teeth 11 from the pins 14 and the arm rests 7 are moved rearwardly or forwardly as desired, until the chair is adjusted to the desired position, whereupon the teeth 11 are again engaged with the pins 14 to maintain the chair in its adjusted position. It will be seen that the chair may be 45 adjusted by the person occupying the chair, it being merely necessary to move the body so as to bear the weight upon the chair seat either forwardly or rearwardly.

When it is desired to fold the chair, the members 15 are moved so that the heads 19 of the rods are in alinement with the enlarged portions of the loops 22 so that the rods may be readily removed, whereupon

the entire chair may be folded to a compact form by raising the chair from the floor and 65 forcing the rod 16 and the cross bar 29 toward each other so that the links 6 turn the legs 3 and the standards 4 on their pivots, as clearly illustrated in Fig. 2 of the drawing. As the bracket 30 is supported below 70 the members 18 and inwardly of their ends, the distance between the brackets and the foot rest will be greater when the chair is in a reclining position than it is when the chair is in a sitting position. This is desirable because a person stretches out when reclining.

While the construction illustrated in the accompanying drawings is the preferred embodiment of my invention, it will be understood that minor changes in construction may be made without departing from the spirit of my invention, or sacrificing any of its advantages as determined by the scope of the appended claims.

Having thus fully described my invention, 85 what I desire to claim and secure by Letters Patent is:—

1. A folding chair comprising crossed pivotally connected legs, a chair back pivotally connected to the upper ends of one pair of legs, standards pivotally connected near their upper ends to the upper ends of the other pair of legs, a chair seat carried by said chair back and said standards, chair arms pivotally connected at their rear ends 90 to said chair back, said arms being slidably and adjustably connected at their forward ends to the upper ends of said standards, and means for holding said standards in a vertical position when the chair is in its 95 set up position.

2. A folding chair comprising crossed pivotally connected legs, a chair back pivotally connected to the upper ends of one pair of legs, standards pivotally connected near 105 their upper ends to the other pair of legs, means for normally holding said standards in an upright position, a chair seat carried by said standards and said chair back, offset plates connected to the upper ends of said 110 standards above said chair seat, pins having their opposite ends connected in the spaced portions of said plates and in the standards, chair arms pivotally connected at their rear ends to the chair back, and rack 115 bars connected to the under faces of the arms at their forward ends for engagement with said pins between the offset portions of the plates and the standards.

In testimony whereof I hereunto affix my 120 signature in the presence of two witnesses.

FRANK J. LASKOWSKI.
